UNITED STATES PATENT OFFICE.

MANUEL BRETOS Y CLAVERIA, OF SANTIAGO DE CUBA, CUBA.

FOLDING DOOR AND SHUTTER.

1,405,758.

Specification of Letters Patent. Patented Feb. 7, 1922.

Application filed July 26, 1920. Serial No. 399,154.

To all whom it may concern:

Be it known that I, MANUEL BRETOS Y CLAVERIA, a subject of the King of Spain, residing at No. 22 Gallo Street, Santiago de Cuba, Cuba, have invented a new and useful Folding Door and Shutter, of which the following is a specification.

By means of my improvement I provide a very useful means in the cooperating elements of the folding doors and shutters, thus obviating the deficiencies which I had discovered by my own experience.

For instance, I obtain a modification in the spring drums of the corrugated metallic doors.

Another advantage consists in providing an improvement in the supports for the door axis.

Another advantage consists in providing a plate for inserting the locks for doors and shutters.

Another advantage consists in a modification in the safety pins for the holding or fastening latches or bolts and in the bolt-clasp or screw nut adjustment.

Another advantage consists in a hook provided with an embedding arm for securing the tracks to the door jambs.

Another advantage consists in an improvement in the engaging bolts for the hooks used to raise and lower the door.

Another improvement consists in the modification of said hooks.

Another advantage consists in a pin or door stop placed in the lower part of the metallic corrugated door in order to hold same with the upper jamb post of the door frame.

Other advantages and purposes of the invention will be understood in the course of this description wherein reference is made to the accompanying drawings, wherein:

Fig. 1 represents a general view of the drum.

Fig. 2 represents a section through A—B of the same.

Fig. 3 represents a section through C—D of Fig. 1.

Fig. 4 is a side view of the drum through the face of the cover.

Fig. 5 is a view of the holding axle-box of the drum.

Fig. 6 is a detail of the lock nut of the axle-box.

Fig. 7 is a detail view of the holding or supporting washer of the rollers.

Fig. 8 is a detail view of a friction roller.

Fig. 9 represents a section through C—D, of Fig. 10.

Fig. 10 is a general view of the supporting device.

Fig. 11 is a detail side view of the same.

Fig. 12 is a similar view of the same.

In Figures 1, 2, 3, 4, 5, 6, 7 and 8, 65 1 represents a drum provided with its cover 8, having openings through which pass the grooved ears 4' of the body of the drum by means of which the pins 9 provide a wedge closing. The bottom of said drum 70 carries a stock or bushing 2 which constitutes a case or bushing for the friction rollers 13, which are kept in position by means of the washer 15'. The cover also carries the same stock or bushing indicated 75 at 2, being exactly equal to that at the opposite side.

The drum rotates around the axle box which makes a frictional adjustment in the axis of the door. The sockets 2 have at 80 their periphery the perforation 6 through which they can operate the key which will tighten the springs which, as is done in the case of ordinary drums, are rolled up in the interior of the drum 1, but in the 85 case herein illustrated the axle box is provided with a claw 13' where the end of the spring 14 is engaged.

The ends 10 of the axle box have a conical thread provided with the expansion grooves 90 15, there being secured at each side screw nuts 15', provided with cuts or grooves 17, so that on being operated by means of a suitable key they will tighten the axle box 95 on the shaft.

The drum has around it the eye 10' with which the strap 7 of the door engages.

In Figs. 9, 10 and 11 and 12 are illustrated the modifications which I have made in the supporting devices of the shaft of the 100 door, which are represented by a supporting arm or bracket shelf of the T-shaped section at its center 23, its ends projecting in oblique directions to that central part, one of said ends being provided with 105 groups 26, over which the head screw 15 slides along the guiding recess 17', being jointed to the die 12, the upper part of which is the ring bracket 22, thereby securing the screw 24, in the door shaft which 110

crosses the ring 22. The joint of transverse grooves 26, or arm 23' of the die movably secure these pieces by means of the screw 15, permitting to graduate the shaft 5 in any position. The screws 16 fix the graduating support to the facing.

Claims:-

1. Improvements in folding doors and shutters by means of which the door and shutter winding drum are formed by a hollow drum with a fixed bottom, and removable cover, there being inserted in said bottom and the removable cover bushing or sockets which constitute bearing cases or 15 bushes to enclose sets of ball bearings or frictional rollers around the axle box which makes a frictional adjustment in the shafts of the door; fastening devices for the bearings, such as holding washers; a claw arranged in the part of the axle box within the drum, wherein the end of the spring engages as is usually done in all drums; 20 means to tighten this spring, such as peripheral perforations in the sockets or stocks; 25 means for tightening the axle box on the

axis, such as expansion grooves; threaded at their conical ends, threaded screw nuts with heads provided with notches in order to facilitate the operation of tightening, means to engage the door strap, such as 30 clasps made from one side of the drum where the strap engages, substantially as herein described.

2. Improvements in folding doors and shutters by means of which a graduate support is provided for the shaft of the door, composed of an arm or bracket of any section inserted in the parament or facing where the door or shutter is placed, bearing at its other end a joint set formed by 35 a bracket of the shaft, the lower part of which is provided with a groove for joining to the transversal groove of the arm by means of a nut which slides along the guiding recesses made in the transversal 40 grooves of the arm, substantially as described.

In testimony whereof I affix my signature.

MANUEL BRETOS y CLAVERIA.
